ATTORNEYS

UNITED STATES PATENT OFFICE.

ROBERT L. BENNETT, OF NEW YORK, N. Y.

FUEL MIXER.

Application filed January 17, 1923. Serial No. 613,189.

To all whom it may concern.

Be it known that I, ROBERT L. BENNETT, a citizen of the United States, and a resident of the city of New York, borough of the Bronx, in the county of Bronx and State of New York, have invented a new and Improved Fuel Mixer, of which the following is a full, clear, and exact description.

My invention relates to a mixer, and aims to provide a device of this character more particularly adapted for use in connection with the preparation of a fuel charge, such as is utilized in an internal combustion engine.

It is a well appreciated fact that the boiling point of volatile fluids such as gasoline, has been constantly decreasing for a number of well-known reasons. Thus it has been increasingly difficult to provide a fuel mixture in which the maximum amount of power will be presented to the consuming element.

For this reason, a number of defects have presented themselves, to wit, that an excess of fuel was necessary to permit of the production of a fuel mixture capable of giving satisfactory results, and due to the necessity of the utilization of this excess, a great amount of carbon deposits have formed in the consuming element resulting in an inefficient operation.

Also this excess of fuel, has, in the case of internal combustion engines worked past the pistons and diluted the lubricating oil, which, as is known, results in serious damage to the working parts of the engine.

Further, if the proportion of fuel utilized is reduced, it is also well known by those conversant with the art, that the engine will be incapable of ready acceleration, and will not develop its maximum power output.

This is to be attributed to the fact that, as aforesigned, the fuel is not readily vaporized, and if the proper proportions are utilized, it will be found that the particles of the fuel will not be evenly distributed, thoroughly broken up, and intimately co-mingled in the fluid acting as a vehicle, and producing with the fluid fuel, the fuel mixture desired. Thus, incident to this uneven distribution, and the low vaporizing qualities of the fuel, a great amount of the same will be deposited in the form of drops on the side walls of the intake manifold, and the fuel mixture will present pockets of rarefied and dense fuel content, which will result in an extremely spasmodic and in-

efficient operation of the engine, where this is the consuming element.

With this in mind, I have constructed a mixer, which is readily applicable to any conventional type of fuel producing and consuming element, and by means of which, primarily, it will be possible for an operator to more nearly utilize the ideal proportions of air and fuel which will result in a more perfect combustion.

A further object of my invention is the construction of a device of the nature stated in which particles of the fuel will be minutely subdivided, and thoroughly and evenly distributed in the fuel mixture.

Still another object of my invention is the construction of a device of the nature stated which is extremely simple in construction, and is hence capable of being manufactured at a nominal figure.

Further objects of my invention will appear in the annexed specification, taken in connection with the drawings, which latter present one practical embodiment of the same, and in which:

Figure 1 is a sectional plan view of my mixer, and showing the same arranged in proper relationship with respect to a fuel vaporizing and consuming element, and

Figure 2 is a sectional view taken along the line 2—2 and in the direction of the arrows indicated in Figure 1.

Referring now more particularly to Figure 1, it will be noted that I have shown my invention as applied to a consuming element, presenting an intake manifold 5, and an exhaust manifold 6.

Also a fuel vaporizing element 7 comprising a carburetor of any desired type is provided, and my improved mixer is arranged in interposed relationship between the fuel vaporizing element 7 and the intake manifold 5, and more particularly between the gasket engaging shoulders 8 usually forming part of these elements.

Assuming that my mixer is to be applied to an already assembled unit, it will be seen that this may be accomplished by removing the gasket (not shown) from between the shoulders 8, and substituting in lieu thereof, a hollow gasket 9 forming a part of my mixer.

This latter gasket is preferably annular to conform to the inner face of the intake manifold 5 and presents in its inner face an annular channel 10.

Associated with the gasket 9 and covering the channel 10, is a cap-shaped plate 11, which plate preferably mounts a screen 12 extending transversely with respect to the flow of fluid, it being also noted that the plate 11 has a series of perforations 13 formed in its face, which perforations are in line with the channel 10 and provide a source of communication between this portion of the intake manifold 5.

I also utilize, as a part of my invention, a hot air intake preferably in the nature of what is commonly known as a "hot stove" 14, which is coupled to the exhaust manifold 6, and has a tube 15 secured to it through which heated air may be drawn to a housing 16. Within this housing is arranged a valve seat with which the rear valve 17 co-operates, thus providing an automatic regulating means for preventing a sudden in-rush of heated air into the housing 16.

A screen 18 may also be arranged within the lower end of the housing 16, and serves to prevent the entrance of foreign matter into the passage 19, which in turn has its outer end in communication with the channel 10.

Thus it will be seen that upon the vaporizer 7 functioning in the usual manner and introducing a fuel mixture into the intake manifold 5, that a regulated supply of heated air is introduced by means of the gasket 9, in the fuel mixture, at a number of different radial points, incident to the suction, which the fuel mixture will produce within the channel 10.

Now with a view of insuring a thorough co-mingling of the fuel particles with the air, and an even distribution of these particles within the fuel mixture, it will be noted that the cap plate 11 has its head formed with a plurality of cutout portions 20 within which a series of deflector blades 21 extend. Thus it will be seen that subsequent to the introduction of the heated additional air into the fuel mixture, that this mixture has imparted to it a whirling motion which will obviously result in a thorough distribution of the fuel particles, and an even mixture.

From the foregoing it will be appreciated that by means of my improved mixer no alteration of structure will be necessary in a unit comprising a fuel producing and consuming element, and that the fuel mixture may be produced within the vaporizer in the usual manner, subsequent to which it

will pass through the screen 12 which will result in the particles of fuel being broken into minute particles. After this has occurred, an additional supply of heated air will be introduced into the fuel mixture in such a ratio that the mixture will embody substantially correct theoretical proportions necessary for efficient operation, and maximum power being delivered on the part of the consuming element.

Finally to insure the proper distribution of the additional air within the fuel mixture, it will be seen that the blades 21 are utilized for accomplishing this purpose, it being also noted that the amount of air for insuring this proper proportion will not be exceeded by virtue of the automatic control established by the valve 17.

Also it will be understood that numerous modifications of structure might be resorted to without in the least departing from the spirit of my invention.

I claim:

1. A mixer, including a gasket presenting a channel in its inner face, a cap plate covering said channel, said plate being formed with a series of perforations in line with said channel, the head of said cap plate being formed with a series of cutout portions, and plates arranged in said cutout portions.

2. A mixer, including a gasket formed with a channel in its inner face, a cap plate carried by said gasket and having its side walls covering said channel, said side walls being covered with a series of perforations in line with said channel, the head of said cap being formed with a plurality of cutout deflector blades within said cutout portions, a housing in communication with said channel, means for introducing heated air into said housing, and a valve co-operating with a valve seat also within said housing.

3. A mixer, including a gasket formed with a channel in its inner face, a cap plate carried by said gasket and having its side walls covering said channel, said side walls being covered with a series of perforations in line with said channel, the head of said cap being formed with a plurality of cutout deflector blades within said cutout portions, a housing in communication with said channel, means for introducing heated air into said housing, a valve co-operating with a valve seat also within said housing, and a screen arranged in advance of said valve.

ROBERT L. BENNETT.
